UNITED STATES PATENT OFFICE.

GEORGE STYER, OF CINCINNATI, OHIO, ASSIGNOR OF ONE-HALF TO
BERNARD FLOTEMERSCHI, OF SAME PLACE.

DESIGN FOR A VIATICUM CRUCIFIX.

SPECIFICATION forming part of Design No. 27,249, dated June 29, 1897.

Application filed February 4, 1897. Serial No. 622,046. Term of patent 7 years.

To all whom it may concern:

Be it known that I, GEORGE STYER, a citizen of the United States, and a resident of Cincinnati, in the county of Hamilton and 5 State of Ohio, have invented and produced a new and original Design for a Viaticum Crucifix, of which the following is a specification.

My invention will be understood from the following description of the accompanying 10 drawing, which is a front elevation illustrating my design.

The leading feature of my design is a cross with its foliated finials, the shell-shaped fount near its base, the looped bracket-arms apparently branching from each edge of the cross 15 near its base and terminating at their outer ends in shell-shaped dishes.

Describing my design in detail, A is the base, cone-shaped and circular in general contour; B, the body of the cross; C, the candelabrum arms or brackets, and D the holy-water fount. The general contour of the base A is not material. The one shown, however, forms a pleasing contrast to the ornamented 25 parts above. The front edges of the cross-body are plain fillets b, which surround a sunken frosted panel. The top and ends of the arms terminate in foliated finials B', formed after the Louis Quatorze style. The 30 foot of the cross above the base is ornamented with foliage, and above the fount D the shaft is encircled by a collar b', having plain fillets at each end and leaf-molding between the fillets. Above the collar is also a foliated or-

nament b². Above the head of the figure is 35 a Maltese cross b³, surrounded by a plain halo or circle.

In front of the cross-shaft between the base A and the collar is a shell-shaped fount D, and springing from behind it upon each side are 40 the bracket-arms C, which curve up in arcs in a plane slightly above the top of the collar b', from which point the arms extend horizontally and are turned in loops c, the terminal of the loop being substantially in the plane 45 of the top of the arm. The shaft of the bracket C is a round bead, the ends finishing in tulips c', and the extreme ends c² are ornamented scrolls from which spring upright rods terminating in tulips c³, which apparently support the shell-shaped dishes E, from the center of which spring the plain tubular cups or 50 sockets F, which receive the candles G. The upwardly-curved portion of the bracket C and the collar b' are connected by spandrels 55 H, which, like the finials of the cross, are in the Louis Quatorze style of ornamentation, and around the plain shaft or bead of the bracket, upon each side between the upwardly-curved portion and the loop c, is 60 twined ornamental foliage c⁴.

What I claim is—

The design for a viaticum crucifix, substantially as herein shown and described.

GEORGE STYER.
